LEON MANN, OF MOUNT VERNON, NEW YORK, ASSIGNOR TO HOLED-TITE PACKING CORPORATION, A CORPORATION OF NEW YORK

CUSHION SEAT

Application filed June 2, 1928. Serial No. 282,396.

The improvements relate to a portable protective covering or seat adapted to be used by spectators at athletic events and serving as an auxiliary seat or cushion, affording comfort to the user as well as protection to his clothing. The improvements are also adapted for use as seats on benches, chairs, steps, lawns or by campers and in fact in any environment where a hard unyielding surface is presented and adapted to support an individual in a sitting posture. A primary object, among others, is the production of an article of manufacture of the aforementioned character of highly efficient form, in such a manner and of such materials that the strength, durability and usefulness of the unit are increased and the cost of production decreased to a minimum.

In practicing the present improvements upstanding supports of substantially conical form are formed in a sheet, preferably of non-metallic material, simultaneously with the formation of said sheet. The formation of the sheets and the projecting supports being preferably accomplished by one and the same process or series of operations, which also includes the formation of a web or cup-like connecting and reinforcing portion extending over the space circumscribed by the edges of said supports, the pitch or inclination of the outer walls of the supports being in the opposite direction to that of its inner walls, which, with the bottom portion, form a cup-like interior. It will be seen from the foregoing and as the description proceeds, that a series of crater-like protuberances or cushions are formed in the sheet of material as an integral part thereof, in one and the same process.

In forming the sheet and parts thereof, wood pulp, cellulose or other fibrous material is employed, the fibres being first placed in a liquid bath. Macerated paper, thoroughly disintegrated and mixed with water until it has the consistency of thick soup may be employed, as may other similar materials. The formation of the sheets may then be accomplished by molding or felting by means of suitable dies or molds, whereby a sheet of relatively yieldable material results, with the

forementioned double arched cushions therein, all consisting of intimately matted fibres. If desired, and particularly where the nature of the fibre employed renders it advisable, a hardening substance such as 55 Portland cement may be added to the bath in quantity sufficient to secure the desired result, but this is not necessary or essential.

The advantages of the present improvements will be apparent. These sheets and 60 cushions therein are of such form and are so constructed and arranged as to be relatively rigid, and yet have a sufficient degree of elasticity to accommodate themselves to pressure exerted thereon. Moreover the nature 65 of the construction insures proper and accurate form and the preservation of that form in use, since any pressure on the sheet or any part thereof will tend to move its matted fibres from their normal position into 70 a more intimate union and will be constantly resisted thereby, to the end that the parts will always have a tendency to return to their original form, which causes them to exert a counter pressure when slightly pressed or 75 drawn therefrom. An inherent resilience and elasticity is thus present in the sheets and parts thus formed, resulting in a cushioning effect under the influence of pressure of the human body or other weight placed thereon. 80

Other advantages will be apparent to those skilled in the art upon reference to the accompanying specification and drawing in which—

Fig. 1 is a plan view of one embodiment of 85 the present improvements;

Fig. 2 is an enlarged section taken on line 2—2 of Fig. 1;

Figs. 3 and 4 are modifications;

Fig. 5 is a side elevation of the form illustrated in Fig. 1, with top folded down in condition for use. 90

In the preferred form illustrated in Fig. 1, the seat comprises a sheet 6 consisting of a bottom portion 7 and top portion 8 formed of unfinished pulp material as above described, the portions being formed or cut to the shape illustrated, although any other convenient outline may be employed. Transverse score lines 9 are made intermediate the 95 100

sheet 6, thus providing a hinge, whereby cover 8 may be readily folded over bottom 7 so that the peripheries thereof coincide, as seen in Fig. 5. Obviously, instead of an integral sheet 6, the portions 7 and 8 may be 5 separate sheets secured together by cloth, cardboard or any other suitable hinge at the point of score lines 9.

Preferably a suitable catch or securing 10 means for holding together the free ends of cover 8 and bottom 7 is provided, as for example, slot 10, and tab or finger 11. It is understood, however, that the parts, when pressure is exerted thereon, will be in the position illustrated in Fig. 5, so that locking 15 means 10 and 11 may be omitted, if desired.

The bottom portion 7, as illustrated, is provided with a plurality of raised frusto-conical members, designated in general by the 20 character 12, formed in the sheet as above described. The arrangement of these members in the sheet may be in any manner desired, as for example in parallel rows, concentric circles or otherwise, although even distribution 25 thereof, so that the members are an equal distance apart, is preferable. The portions 13 of the sheet between members 12 are preferably flat and in the same horizontal plane so as to present an even surface upon which top 30 8 may rest. In the event that members 12 are formed closer to one another, the portions 13 may be rounded, the particular form thereof not being essential.

Each member 12 consists of a downwardly 35 and inwardly inclined wall 14 and an upwardly and inwardly inclined interior wall 15 with a dome-shaped bottom 16 but the angles and arrangement of these parts may be varied to some extent, but it is important that 40 the ring 17 defined by the union of walls 14 and 15 be in substantially the same plane as rings 17 of the other members. The dome-shaped central portion 16 of the member 12 extends to the plane of portions 13 of the sheet 45 (as seen in Fig. 2) and provides therewith a supporting surface for the top 8.

As illustrated the top or cover portion 8 (likewise of unfinished pulp material) presents a smooth seating surface and may be 50 ironed and sized so as to receive lettering or printing embodying advertisements and the like.

In use, the top 8 is folded over bottom 7, and placed with members 12 on the supporting 55 surface 18, so that top 8 with or without advertising matter, faces upward, thus presenting a smooth seat for the user.

The form of each cushion member 12 is substantially that of an arch, of which the surface 18 is the keystone so that great strength, durability and resistance to pressure is obtained and the tendency of such pressure to deform and break down the member 12 is resisted. Thus downward pressure 65 on portions 13 and onto the walls 14 (see Fig.

5) tends to urge the fibres of the sheet material closer together (which they constantly resist) and consequently instead of spreading or giving way, the members 12 retain their form, being only more closely matted together under the pressure, upon release of which they return to their normal position. A soft cushioning effect thus results, from the inherent character of the sheet material and the form of the protuberances 12. 75

This cushioning function is also contributed in like manner by the inclined walls 15 and dome-shaped member 16 which form in effect a reverse arch, pressure on domes 16, through walls 15 to ring 17 being resisted 80 by a like movement of the fibres, which spring back to normal position when pressure is removed.

It is thus seen upon inspection of Figs. 1 and 2, that pressure upon a dome 16 tending 85 to spread wall 15 thereof is resisted by the ubiquitous portions 13 exerting a like pressure through walls 14. Conversely, the tendency of walls 14 to spread under pressure is resisted by the adjacent walls 15 and domes 90 16. Obviously therefore, the bottom portion 7 is provided with an infinitesimal number of substantially V-shaped supports which greatly contribute to the strength and durability 95 of the construction but yet are yielding due to the inherent characteristics of the material, as above set forth.

It will be noted that a seat of the character described is called upon to withstand not only strains in a vertical direction but also lateral 100 and twisting strains of every description. Accordingly the improvements of the present disclosure have been so designed that the protuberances affording the cushion members, are capable of resisting the lateral, oblique and twisting strains caused by the weight of the human body seated thereon as well as satisfying the primary function of 105 resisting strains in a vertical plane.

Furthermore, the arrangement of the members 12 is such that air pockets 19 and 20 exist when the article is in use tending to form a plurality of air cushions to supplement the inherent elasticity of the article itself. 110

Aside from affording a smooth seating surface, the cover 8 when in use, rests upon the portions 13 and domes 16 which latter are in substantially the same horizontal plane, and accordingly cover 8 serves to distribute the weight throughout the said portions and domes of bottom sheet 7. In turn the weight is borne in like manner by the rings 17 which are also all in the same plane and accordingly each ring 17 contacts the supporting surface 18 and bears a fractional part of the total 115 weight. 120

It is apparent that when a plurality of the articles herein described are stacked for shipment, vending or carriage under one's arm in unfolded position as seen in Fig. 1, they may 130

be conveniently nested by placing the bottom portions 7 of the sheets alternately on the right and left of the stack so that a pile of even dimensions results.

5 The foregoing improvements accordingly provide a cheap and highly efficient cushion seat which embodies characteristics of comfort and may be easily distributed to the public for extended or limited use as desired. 10 Due to the light weight of the article, it may be readily moved or carried without inconvenience by the user. Essentials of strength and durability, however, have not been sacrificed in the interest of lightness and portability, for with the present improvements the pressure of the human body on the seat is evenly distributed throughout the cushion members 12, so that a fractional part of the total weight is borne by each, and accordingly 15 each cooperate with the other in producing a sturdy yet relatively yieldable seat. It is apparent that the cushion effect is contributed to by the entire seat comprising the top and bottom members 7 and 8, since the whole 20 sheet, being made of the unfinished pulp material, will respond to pressure after the manner indicated.

Due to the relatively flexible character of the entire seat as described, it is apparent 30 that same will function with equal efficiency should the supporting surface 18 be uneven, in which event the entire sheet (as well as the parts thereof) will accommodate itself to the environment and function as described.

35 Instead of the plurality of raised members 12, a similar cushion effect may be obtained by forming the bottom portion 7' with a plurality of spaced ribs 21 formed in the sheet as described. This form is shown in 40 Fig. 3 with a space 22 provided for advertising, if desired.

In Fig. 4, a plurality of diagonal ribs 23 intersecting each other, are illustrated. These ribs are formed in the bottom 7'', as in 45 the preferred form and by reason of their intersection form diamond shaped cavities 24 which define air pockets with the supporting surface, as previously referred to. As in the preferred form, these ribs have inclined walls 50 and thereby resist the pressure distributed throughout same, and possess similar resilient characteristics. Furthermore the intersecting ribs, like the members 12 of the form initially described, resist crushing (due to the 55 converging walls thereof) such as may occur from lateral pressure resulting from an individual sliding about on the seat. It is understood, of course, that the forms illustrated in Figs. 3 and 4 are also provided with covers 8, 60 which has been omitted in these figures for convenience of illustration.

Various other modifications within the scope of the present improvements, will occur to those familiar with the art. For example, 65 two covers 8 may be provided, if desired, for

use above and beneath the sheet 7. Furthermore, if desired, domes 16 may be formed with a depression forming a shallow dished portion, thereby presenting a supporting ring in the plane of portions 13. 70

I claim:

1. A cushion seat of the character described comprising a plurality of sheet sections formed of unfinished pulp material, one of said sections having a relatively smooth 75 surface, and another section having frusto-conical protuberances associated therewith.

2. A cushion seat of the character described comprising a plurality of sheet sections formed of unfinished pulp material, 80 one of said sections having a relatively smooth surface and another section having frusto-conical protuberances including a dome-shaped portion associated with said section. 85

3. In a seat of the character described, a cushion element comprising a sheet of unfinished pulp material having thereon a series of projecting cushion members each consisting of an annular upstanding rim of 90 substantially frusto-conical form and a supporting web for each member bridging the rims thereof.

4. In a seat of the character described, a cushion member comprising a sheet of unfinished pulp material having thereon a series of unbroken protuberances each consisting of an annular upstanding rim of substantially frusto-conical form and a dome-shaped member extending from said rim 100 with its apex substantially in the plane of the base of said frusto-conical member. 95

5. A cushion seat comprising a nonplaniform sheet of material composed of felted fibres in normal positions in the said nonplaniform state of the sheet and so arranged that stresses or strains tending to flatten the sheet will tend to move the said fibres from their normal felted or matted positions and relations and will be resisted by the 105 tendency of said fibres to remain in such normal positions and relations, said sheet having separated arched portions connected by lateral portions, the former adapted to 110 yieldingly support weight and pressure superposed thereon and the latter to receive and distribute such weight and pressure. 115

Witness my hand this 1st day of June, 1928, county of New York, State of New York. 120
